CLAIM

The ornamental design for a cover for a faucet mounted water filter, as shown and described.

DESCRIPTION

FIG. 1 is a perspective view of a cover for a faucet mounted water filter showing my new design, the broken line drawing of a filter unit is shown for illustrative purposes only and forms no part of the claimed design; FIG. 2 is a front elevational view thereof, the rear view being a mirror image;

FIG. 3 is a top plan view thereof;

FIG. 4 is a bottom plan view thereof;

FIG. 5 is a right side elevational view thereof; and,

FIG. 6 is the left side elevational view thereof.

FIG. 1

FIG. 2

FIG. 3

FIG. 4

FIG. 5

FIG. 6
